UNITED STATES PATENT OFFICE.

NATHAN M. LOWER, OF SCHENECTADY, NEW YORK, ASSIGNOR TO LOCOMOTIVE STOKER COMPANY, OF PITTSBURGH, PENNSYLVANIA, A CORPORATION OF PENNSYLVANIA.

AUTOMATIC STOKER MECHANISM.

1,259,643.

Specification of Letters Patent. Patented Mar. 19, 1918.

Application filed June 28, 1915. Serial No. 36,809.

To all whom it may concern:

Be it known that I, NATHAN M. LOWER, a resident of Schenectady, in the county of Schenectady and State of New York, have 5 invented a new and useful Improvement in Automatic Stoker Mechanism, of which the following is a specification.

This invention relates to stoker mechanism for supplying fuel to the fire boxes of 10 steam boilers. One object of the invention is to provide improved mechanism of this kind which enables the fuel to be supplied at several different uniform or stable rates to 15 compensate for varying conditions of fuel consumption, or, in other words, stoker mechanism which can be controlled to permit stable operation of the boiler at any desired rate of input of fuel to the fire box.

Most stoker mechanisms, and particularly 20 locomotive stoker mechanism, which is only one form to which the invention may be applied, are operated by a fluid pressure engine, such as a compressed air or steam engine, a gas engine or the like. These engines are built to run at a fixed or set speed, 25 being usually provided with governor devices to confine the speed closely to that which is most economical in the particular engine, and they cannot be set to run at any 30 one of a number of different speeds, even by manipulation of the throttle, due to variations in load or the pressure of the fluid supply, which changes the rate of delivery 35 of the power to the engine. Another object of the invention is therefore to provide power operated stoker mechanism embodying a driving engine and devices so arranged 40 as to permit said engine, preferably while running, to be set to run at any desired stable or uniform speed, so as to maintain uniform any particular rate of feed of the fuel 45 to the fire box.

Further objects of the invention are in part obvious and in part will appear more 50 in detail hereinafter.

In the drawings, which represent one embodiment of the invention, Figure 1 is an end elevation of a locomotive equipped with 55 automatic stoker mechanism embodying the invention; Fig. 2 is a longitudinal sectional view thereof, with the stoker mechanism in side elevation; Fig. 3 is a detail sectional view on the line of the engine crank shaft, some parts being shown in elevation, and 60 illustrating the governor device and the con-

nection to the automatic stoker mechanism; Fig. 4 is a detail sectional view on the line 4—4, Fig. 3, and showing some of the parts in elevation; Fig. 5 is a detail sectional view on the line 5—5, Fig. 3, the governor 60 weights being in retracted position; Fig. 6 is a detail sectional view on the line 6—6, Fig. 3, the governor weights being in their outer position; Fig. 7 is a view corresponding to Fig. 5, the governor weights being shown in 65 their outer positions; Fig. 8 is a detail view of a lever; Fig. 9 is a cross sectional detail on the line 9—9, Fig. 3; and Figs. 10 and 11 are diagrammatic views showing the eccentric 70 of the governor device, and parts associated therewith, in two different positions.

The invention may be applied to any form of stoker mechanism, such as automatic stoker mechanism for a stationary steam boiler installation, a marine boiler, or any 75 other power plant employing a fire box for producing heat. For convenience of illustration, it has been shown in the drawings as applied to automatic locomotive stoker mechanism, which may be of any suitable 80 type, such for example, as either of the stoker mechanisms shown in my prior applications, Serial Nos. 672,334, filed January 20, 1912, and 726,108, filed October 16, 1912, and it will be understood that any of the 85 devices shown in said applications may be used in connection with the present invention. In the drawings, the automatic locomotive stoker mechanism is illustrated as of the 90 same construction and arrangement as in the patent to C. F. Street, 1,130,443, dated March 2, 1915, and will therefore be only briefly described, it being understood that all features of the mechanism shown for 95 supplying the fuel from the tender to the locomotive fire box are the same as shown in said patent.

Referring to the drawings, the stoker mechanism is shown applied to an engine 1 and tender 2, the engine being provided with the usual fire box. The stoker mechanism comprises a suitable crushing mechanism 3, shown as of the jaw type, located on the tender, and which delivers the crushed fuel to a chute or conveyer 4 through which it travels to a fuel receptacle 5, preferably located beneath the deck of the locomotive. As will be understood the crushing mechanism 3 may be omitted and the fuel supplied to the tender in a crushed condition for de- 105 110

livery directly by gravity or through a suitable conveyer to the fuel receptacle 5. The fuel is conveyed from the receptacle 5 to the fire box by an endless chain provided with 5 a series of buckets, said chain working in a hollow conduit, the two legs 6 of which are located at the sides of the ordinary firing opening. The conveyer chain is guided by and runs over sprockets 7, the upper one of 10 which is on a shaft 8 carrying a worm wheel driven by a worm 9 on the crank shaft 10 of a suitable fluid pressure engine, such as a steam engine or the like. The buckets deliver the fuel to a hopper 9^a from which it 15 flows by one or more conduits 9^b to one or a plurality of fuel injecting devices 9^c, which force or inject it into the locomotive fire box. These fuel injecting devices may be of any suitable form and require no further description, but they are shown as of the same type 20 illustrated in the Street patent referred to, and are operated by steam pressure controlled by cam mechanism 9^d, so as to produce operations of the several injectors at 25 varying intervals, depending upon the adjustment of the cam devices.

The steam engine is illustrated at A, its crank shaft 10 being connected by suitable gearing to the shaft carrying the upper 30 sprocket 7, as before described. The engine A may be of any suitable form, say a gas engine or a fluid pressure operated engine run either by compressed air, steam or the like. In the drawings it is shown as a steam 35 engine. It is equipped with some suitable form of governing device or devices enabling the engine to be set, preferably while running, so as to run at any one of a number of predetermined speeds and therefore maintain 40 uniform or stable the speed of operation of the entire locomotive stoker mechanism. This enables fuel to be supplied to the fire box within very narrow limits at a uniform or fixed rate, which rate may be varied in 45 accordance with the required conditions of fuel consumption at any particular time or under any given running conditions. The fireman can therefore speed up his entire locomotive stoker mechanism when the train 50 is traveling up a grade or is unusually heavy, or may decrease its speed when on the level or on a down grade or with a light train.

One suitable form of governor device suitable for this purpose is illustrated in Figs. 55 3 to 9 of the drawings, and is of the same form as that illustrated and described in my prior application for engine governor, filed February 6, 1914, Serial No. 816,925.

The wrist pin of the engine crank shaft 60 is shown at 11. This crank and the governor mechanism are inclosed within a suitable casing 12, from which the valve rod or stem 13 projects, said rod or stem being connected at one end in any suitable manner to 65 the engine valve controlling devices, and at

its other end to a nipple 14 on a strap 15 encircling an eccentric 16. The eccentric is pivotally mounted on a post 17 set in a disk 18 which is fixed upon the shaft 10.

The usual governing weights, of which 70 any number may be used, two being illustrated, are designated 19 and 20, being pivoted upon posts 21, 22 set in the disk 18, said weights being connected by a link 23. The weights are retracted by the usual 75 springs 24, 25 connected thereto and at their opposite ends anchored to the disk 18, at 26 and 27. Said governing weights are also connected to the eccentric 16 by means of a link 28 attached to one of them, as 19, at 80 the point 29.

As so far described the governor is without novel features. In the absence of other elements the outward movement of the governing weights, due to centrifugal forces in 85 excess of the spring tension, swings the eccentric 16 about its pivot 17 so as to cause its center to approach the center of the shaft 10, thereby decreasing the throw of the valve rod 13 and valve and reducing the supply of 90 steam to the engine in the usual manner, thus tending to maintain a uniform fixed speed. Additional mechanism is provided in order to augment the spring tension to 95 correspond at different speeds with the augmentation of the effective centrifugal force as the weights move out, and thereby prevent the action known as pounding, and to also vary the speed at which the governor will act without changing the springs and 100 without stopping the engine, to thereby enable the engine to be operated at several different uniform speeds.

This is accomplished by introducing an additional spring attached at one end to the 105 eccentric 16 and at the other end to the free end of a lever which is swung backwardly by the shifting of the eccentric responsive to the outward movement of the weights; and there is also provided a manually shifted 110 fulcrum for said lever, enabling not only the tension of the supplemental spring to be varied, but also its elongation, due to the movement of the weights, which elongation may be varied to correspond with the centrifugal 115 force of the weights.

Said lever is marked 30 and is pivotally attached at 31 to the eccentric 16 and at the other end to a supplemental spring 32 secured at the far side of the eccentric, although not necessarily diametrically opposite the point 31, it being only important that the points of attachment of the lever and spring to the eccentric be upon opposite sides of the radius to the center of the 125 shaft 10 in which the pivot 17 is located. The fulcrum of the lever preferably takes the form of an antifriction roller 34 carried by a sleeve 35 rotatable and slidable upon the shaft 10. Movement of the eccentric 130

from the position of Fig. 4, where the weights are retracted, toward the position in Fig. 6, where the weights are at their outer position, stretches the spring 32 by 5 separating the points of attachment of its ends, the eccentric being carried to the right and the free end of the lever 30 to the left. The spring 32 therefore not only supplements the springs 24, 25, by its inherent 10 tension, but the increase of its pull is rapidly augmented by the lever action, as the spring is stretched from both ends.

The lever 30 is provided with an oblique channel 36 across its inner face for engagement by the roller 34, which is so located that its axis is oblique to the engine shaft. The shifting of the fulcrum along the channel has the effect of swinging the lever upon its pivot, thereby changing the tension of 20 the spring 32, and this action is augmented by varying the depth of the channel from end to end, its greatest depth being at the end most remote from the pivot 31. The sleeve 35 is shiftable longitudinally by a 25 hand lever 37, located for convenient access by the fireman, and mounted upon a shaft 38 which extends out through the casing 12, said shaft carrying a yoke 39 lying within the casing and having arms connected by 30 links 40 to studs 41 upon a shifting annulus 42 associated with the sleeve.

The sleeve 35 bears directly upon the forward end of the shaft 10, as at 43. At its rearward end it is counterbored to loosely 35 receive a sleeve 44 which fits upon the shaft, the extreme end of the sleeve 35 being enlarged to form a hub 45 within which is located a ball bearing casing 46, the inner member of which is mounted upon the sleeve 40 44 and abuts against a flange thereof. The shifting annulus 42 is held between an annulus 47 secured to the hub 45, as by being threaded on a flange 48 thereof and an annulus 49 on the sleeve 44, a wear plate 51 45 being preferably interposed between the annulus 47 and the annulus 42.

An annular wear plate 52 is fixed upon the shaft 10 back of the annulus 49 and bears against the inner end of a box 53 50 within which one portion of the shaft 10 is journaled. For locking the annulus 52 to the shaft there are provided two semi-circular plates 54, 55, which fit within a recess of the annulus 52 and are secured 55 thereto by stud or dowel pins 56, 57, entering recesses in the annulus. The plates 54, 55, are also seated in a circumferential channel in the shaft 10, said channel being interrupted by stop shoulders 58, 59, entering 60 recesses in plates 54, 55. Said plates are held against radial outward movement by the walls of the recess in the plate 52 in which they are seated.

The annulus 42 is provided with a lug 65 60 fitting loosely within a recess in the arch

of the yoke 39, which holds the annulus against rotative movement.

On the outside of the casing 12 is located a toothed quadrant 61 which co-operates with a spring latch 62 on the hand lever 37 70 for holding this lever and its associated parts in any one of a number of different positions.

When the lever 37 is in the position shown in Fig. 3 the fulcrum roller 34 occupies 75 the outer end and deepest portion of the oblique channel in the lever 30 and is located at the maximum distance from the pin 31 attaching the lever 30 to the eccentric. The spring 32 is now under minimum 80 tension and the governor acts at the lowest desired speed and maintains said speed uniform so as to operate the entire stoker mechanism slowly and produce a slow, uniform stable feed of the fuel to the locomotive fire box. Shifting the hand lever 37 to the right from the position shown in Fig. 3 advances the fulcrum roller 34 along the inclined channel in the lever 30, which increases the tension of the spring 32 to correspond with the increased centrifugal force 85 of the higher speed of the governor weights when they are in against the shaft. The advance of the fulcrum point along the oblique track also changes the leverage of 95 the spring 30 so that the movement of the weights outward at the higher speed gives an increased elongation of the spring corresponding with the augmented increase of centrifugal force of the weights from in 100 to out position, at the higher speeds. Therefore at the positions of the lever 37 to the right of that shown in Fig. 3 the engine will run at uniform and stable speeds higher than that at which it will run in the position shown, so that the entire mechanism will operate at a higher rate of speed and produce a larger, but nevertheless uniform, supply of fuel to the locomotive fire box. 105

Sleeve 35 is rotatable on the shaft 10 not 110 only to enable the fulcrum roller to move along the oblique channel in the lever 30, but also to provide for movement of said roller relatively to the shaft incident to the change of positions of the eccentric as the governor 115 acts. The pressure exerted by the lever 30 on the lever 35, holding it against the shaft, is mainly supported by the ball bearing 46, thereby reducing the friction and permitting 120 free angular movement of the sleeve incident to the action of the governor.

The action produced by the supplemental spring 32, lever 30 and shiftable fulcrum 34 is best illustrated in the diagrammatic views, Figs. 10 and 11. In Fig. 10 the position of 125 the eccentric 16, supplemental spring 32, lever 30, and fulcrum 34, when the engine is at rest and the adjustment is for low speed of the mechanism, is indicated in full lines. The positions of these parts when the 130

weights have moved outwardly are indicated in dotted lines. It will be observed that the shifting of the eccentric to the right carries the pivot 31 and the end 33 of the 5 spring 32 to the right, while the free end of the lever 30 is moved to the left, carrying with it the opposite end of the spring 32. Thus the spring is stretched from both ends.

- In Fig. 11 the positions of the same parts 10 while the engine is at rest, but with the fulcrum 34 shifted to provide for a higher engine speed, are indicated in full lines, and their positions with the weights moved out, in dotted lines. It will be here observed 15 that as the fulcrum has been moved nearer to the pivot 31, as in Fig. 10, the movement of the free end of the lever 30 to the left, due to the movement of the eccentric, is increased, thereby securing a greater augmentation 20 of centrifugal force as the weights move out at the higher speeds, than results at lower speeds.

- All of the springs 24, 25 and 32 have a re- 25 tracting effect upon the weights 19 and 20. While three springs are preferably used situations may arise in which the spring 32 alone will be sufficient to retract the weight, in which case the springs 24 and 25 may be dispensed with.

- 30 In operation the locomotive fireman adjusts the entire stoker mechanism by manipulation of the lever 37 so as to supply the fuel to the locomotive fire box at the proper rate to maintain a uniform fire under the 35 existing running conditions. If the requirements of the engine demand a large steam supply the fuel must be delivered to the fire box more rapidly, and the lever 37 is pushed over to the right to set the engine to run at 40 a higher but nevertheless uniform speed so as to speed up the operation of the entire stoker mechanism. On the other hand, when the engine is hauling a light train or is traveling on the level or on a down grade, 45 so that only a small steam supply is necessary, the lever 37 can be pushed over to the left to set the engine to run at a lower fixed speed. The engine drives not only the conveyer mechanism for carrying the fuel from 50 the tender to the locomotive, but also the crusher devices for breaking up the fuel, which of course are of a size calculated to deliver all the fuel that the conveying mechanism can take care of. The engine also 55 controls the operation of the fuel injecting devices, which in the form shown are controlled by cam devices driven by the conveying mechanism. Therefore, the speed of the engine determines the operation of the 60 entire stoker mechanism and consequently the rate of supply of the fuel to all parts of the fire box.

What I claim is:—

1. The combination with a locomotive and 65 tender, of means for transferring fuel from

the tender to the locomotive, a fuel injector receiving from said transfer means and delivering the fuel to the locomotive fire box, and a motor having a plurality of constant speed rates for driving said conveyer and 70 controlling said injector.

2. The combination with a locomotive and tender, of means for transferring fuel from the tender to the locomotive, a fuel injector receiving from said transfer means and 75 delivering the fuel to the locomotive fire box, a motor having a plurality of constant speed rates for driving said conveyer and controlling said injector, and means for changing from one motor speed rate to an- 80 other while the motor is in operation.

3. The combination with a locomotive and tender, of stoker mechanism for conveying the fuel from the tender to the locomotive fire box and distributing it over the 85 fire therein, and a motor for driving said stoker mechanism having a plurality of different uniform rates of speed and adapted to vary the quantity of fuel delivered to the fire box in a given unit of time without af- 90 fecting its distribution therein.

4. The combination with a locomotive and tender, of stoker mechanism for conveying the fuel from the tender to the locomotive fire box and distributing it over the fire 95 therein, a motor for driving said stoker mechanism having a plurality of different uniform rates of speed and adapted to vary the quantity of fuel delivered to the fire box in a given unit of time without affecting 100 its distribution therein, and means for changing from one motor speed rate to another while the motor is in operation.

5. The combination with a locomotive and tender, of stoker mechanism for supplying the fuel from the tender to the locomotive fire box, intermittently operating devices for distributing the fuel over the fire therein, a multiple-speed engine for driving said mechanism and controlling said 105 110 devices, and means for changing from one engine speed to another while the engine is in operation.

6. The combination with a locomotive and tender, of means for transferring fuel from 115 the tender to the locomotive, a fuel distributing means receiving from the transfer means and delivering the fuel to the locomotive fire box, and a motor having a plurality of constant speed rates for driving 120 said transferring means and controlling said fuel distributing means.

7. The combination with a locomotive and tender, of means for transferring fuel from the tender to the locomotive, a fuel distributer receiving from said transferring means and delivering the fuel to the locomotive fire box, a motor having a plurality of constant speed rates for driving said transferring 125 means and controlling said distributer, and 130

means for changing from one motor speed 5
rate to another while the motor is in opera-
tion.

8. The combination with a locomotive and
5 tender, of a stoker mechanism for automatic-
ally supplying fuel from the tender to the
fire bed in the locomotive fire box, and a
motor for driving said mechanism having a
plurality of different uniform rates of speed
10 and adapted to vary the quantity of fuel de-
livered to the fire box in a given unit of
time without affecting its distribution
therein.

9. The combination with a locomotive and
15 tender, of a stoker mechanism for automatic-
ally supplying fuel from the tender to the

fire bed in the locomotive fire box, and a
motor for driving said stoker having a plu-
rality of different uniform rates of speed 20
and adapted to vary the quantity of fuel de-
livered to the fire box in a given unit of
time without affecting its distribution
therein, and means for changing from one
motor speed rate to another while the motor
is in operation. 25

In testimony whereof, I have hereunto set
my hand.

NATHAN M. LOWER.
